United States Patent Office

Des. 231,828
Patented June 18, 1974

231,828

GUN AIMING DEVICE

Jack Y. Canon, 2194 Delmas, Opelousas, La. 70570

Filed Aug. 18, 1972, Ser. No. 281,951

Term of patent 14 years

Int. Cl. D22—99

U.S. Cl. D22—7

Fig. 4

Fig. 3

FIG. 1 is a side elevational view of a gun aiming device showing my new design;

FIG. 2 is a top plan view thereof with the wrist portion omitted for convenience of illustration;

FIG. 3 is a perspective view taken from the right of the wrist portion of FIG. 1 with the butt being omitted for convenience of illustration; and

FIG. 4 is a side view of the wrist portion with the butt being omitted for convenience of illustration.

I claim:

The ornamental design for a gun aiming device, substantially as shown and described.
